UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

HOISTING MECHANISM

Application filed September 10, 1931. Serial No. 582,114.

This invention relates to hoisting mechanisms, and more particularly to improvements in hoisting mechanisms of the double drum, portable type.

5 An object of this invention is to provide an improved hoisting mechanism. Another object is to provide an improved hoisting mechanism of the double drum, portable type having an improved arrangement of the hoisting drums and the driving means therefor whereby the hoisting mechanism is rendered extremely compact. A further object is to provide an improved hoisting mechanism of the double drum type having improved 10 drive and control means for the drums. These and other objects will, however, subsequently more fully appear.

In the accompanying drawing there is shown, for purposes of illustration, one form 20 which the invention may assume in practice.

In this drawing,—

Fig. 1 is a central, longitudinally extending, vertical sectional view taken through the 25 illustrative embodiment of the improved hoisting mechanism.

Fig. 2 is a transverse vertical sectional view taken on line 2—2 of Fig. 1.

Fig. 3 is a transverse vertical sectional view taken on line 3—3 of Fig. 1.

30 Fig. 4 is a fragmentary side elevational view illustrating a portion of the improved drum drive control means.

In this illustrative construction there is shown a hoisting mechanism of the double 35 drum, portable type comprising a base 1, herein in the form of a skid, having mounted thereon, a cylindrical housing 2. Closing one end of this housing is a circular plate member 3 supporting a motor 4. Attached to the 40 opposite end of this cylindrical housing is a closure member 5, an intermediate plate 6, and an outer casing 7, the elements 5, 6 and 7 cooperating and form a gear housing for the drum drive gearing. In the present construction, the motor 4, which may be of any 45 suitable form, has a cylindrical casing 8 detachably secured by bolts 9 to the closure member 3, as shown in Fig. 1; and the power shaft 10 of this motor is journaled in a bearing 11 supported within a retaining member

12 positioned within the end closure plate 3. The motor power shaft is splined at 13 to a coupling sleeve 14, which is in turn splined at 15 to a longitudinally extending transmission shaft 16. The shaft 16 is positioned centrally within and rotatable relative to a hollow drive sleeve 17 and is journaled at one end in a bearing 18 positioned within the gear casing 7. Fixed to the shaft 16 adjacent this bearing is a spur gear 19 meshing with a spur gear 20 fixed to a shaft 21 arranged parallel with the shaft 16 and journaled within bearings 22 positioned within the plate 6 and gear casing 7. Fixed to and driven by the shaft 21 is a spur gear 23 meshing with an internal gear 24 keyed at 25 to one end of the drive sleeve 17. This drive sleeve is journaled in bearings 26 supported within the hub portions of the closure members 3 and 5, and has fixed thereto adjacent its opposite ends 60 drum drive gears 27, 28. Journaled on bearings 29 supported by the drive sleeve 17, and driven by the gears 27 and 28, respectively, are winding drums 30 and 31, these drums being arranged within the housing 2 in substantially end abutting relation as shown. 65 Supported on a stub shaft 32 carried by the drum 30 and meshing with the gear 27 is a planetary gear 33 meshing with an internal gear 34 formed on a rotatable reaction member 35. The hub of the member 35 is journaled on a bearing 36 supported by the hub of the adjacent end closure member 5. The drum 31 is driven through a similar transmission including planetary gear 37, internal gear 38, and rotatable reaction member 39. The members 35 and 39 are externally grooved at 40 to form braking surfaces with which cooperate brake bands 41 and 42, respectively. The adjacent ends of the drums 30 and 31 are provided with braking surfaces 43 with which cooperate drum brakes 44 and 45, respectively, each having suitable operating means. The operating means for the drive control brakes 41, 42 may assume various forms and are herein identical in structure, and each comprises an adjusting screw 46 cooperating with nut elements 47 carried within ear members 48 attached to the ends of the brake bands. The adjusting screws 46

are suitably journaled within the lower part of the housing 2 and have fixed thereto at their outer ends levers 49 and 50, respectively. Connecting these levers is a rod 51 suitably 5 pivotally connected at 52 to an operating handle 53. If desired, the controlling means for the brake bands 41, 42 may be provided with separate operating handles so that the brake bands may be independently controlled. Wound on the drums 30, 31 are 10 cables 54, and the cylindrical housing 2 is provided with lateral openings 55 to permit the cables to be extended from the drums outwardly laterally through the housing, as 15 shown in Fig. 3.

The method of use of the improved hoisting mechanism will be clearly apparent from the description given. When the motor 4 is running, the drive sleeve 17 is driven at a 20 reduced speed from the motor power shaft 10 through the transmission shaft 16, reduction gearing 19, 20, 23, 24. When the reaction member 35 frictionally is held against rotation by the brake band 41, and the brake band 25 42 is released, the drum 30 is driven from the drive sleeve 17 through the drive gear 27 and the planetary gear 33 meshing with the teeth of the internal gear 34, the latter being held 30 stationary at that time and the gear 33 rolling around this internal gear as a trackway to effect drum drive. At this time, the drum 31 may freely rotate. When the brake band 41 is released and the brake band 42 is applied, the drum 31 is driven through the 35 gearing 28, 37, 38 while the drum 30 may freely rotate. Either drum when disconnected from its drive may be held against rotation or frictionally braked by the brake bands 44, 45.

40 As a result of this invention, it will be noted that an improved hoisting mechanism is provided having improved drum driving control means. It will further be noted that due to the improved arrangement of the drums and 45 drum driving means, the hoisting mechanism is rendered exceedingly compact. It will further be evident that by the provision of the cylindrical housing the moving parts of the hoisting mechanism are protected, while 50 at the same time these parts may be readily dismantled. These and other uses and advantages of the improved hoisting mechanism will be clearly apparent to those skilled in the art.

55 While in this application there is specifically described one form which the invention may assume in practice, it will be understood that this form is shown for purposes of illustration only and that the invention 60 may be modified and embodied in various other forms without departing from its spirit or the scope of the appended claims.

What I claim as new and desire to secure by Letters Patent is:

65 1. In a hoisting mechanism, a support, a

drive sleeve journaled within said support, relatively rotatable hoisting drums rotatably mounted on said drive sleeve, motor operated driving means for said drive sleeve including a transmission shaft arranged centrally within said drive sleeve and gearing connecting said transmission shaft and said drive sleeve, and a planetary slip control driving connection between said drive sleeve and each of said drums. 70 75

2. In a hoisting mechanism, a support, a drive sleeve journaled within said support, relatively rotatable hoisting drums rotatably mounted on said drive sleeve, motor operated driving means for said drive sleeve including a transmission shaft arranged centrally within said drive sleeve and gearing connecting said transmission shaft and drive sleeve in driving relation, and driving connections between said sleeve and each of said drums, each driving connection including a gear fixed to said sleeve and a gear carried by the drum and meshing with said gear. 80 85

3. In a hoisting mechanism, a support, a drive sleeve journaled within said support, relatively rotatable hoisting drums rotatably mounted on said drive sleeve, motor operated driving means for said drive sleeve including a transmission shaft arranged centrally within said drive sleeve and gearing connecting said transmission shaft and drive sleeve in driving relation, and driving connections between said sleeve and each of said drums, each driving connection including a gear fixed to said sleeve, a gear carried by the drum and meshing with said gear, and a frictionally controlled reaction gear with which said gear carried by said drum meshes. 90 95

4. In a hoisting mechanism, a support, a drive sleeve journaled within said support, relatively rotatable hoisting drums rotatably mounted on said drive sleeve, motor operated driving means for said drive sleeve including a transmission shaft arranged centrally within said drive sleeve and gearing connecting said transmission shaft and drive sleeve in driving relation, and driving connections between said sleeve and each of said drums, each driving connection including a gear fixed to said sleeve, a gear carried by the drum and meshing with said gear, a frictional controlled reaction gear with which said gear carried by said drum meshes, and a brake-band controlling rotation of said re- 100 105 110

action gear. 115

5. In a hoisting mechanism, a base, a cylindrical housing carried by said base, end closure members for said housing, a drive sleeve journaled within said end closure members, relatively rotatable hoisting drums arranged within said housing and rotatably mounted on said drive sleeve, a motor carried by one end closure member, driving connections between said motor and said drive sleeve including a transmission shaft arranged cen- 120 125 130

- trally within said drive sleeve, gearing connecting said shaft and said drive sleeve in driving relation, and frictionally controlled planetary driving connections between said 5 drive sleeve and each of said drums and also arranged within said housing.
6. In a hoisting mechanism, a base, a cylindrical housing carried by said base, end closure members for said housing, a drive sleeve 10 journaled within said end closure members, relatively rotatable hoisting drums arranged within said housing and rotatably mounted on said drive sleeve, a motor carried by one end closure member, driving connections between 15 said motor and said drive sleeve including a transmission shaft arranged centrally within said drive sleeve, gearing connecting said shaft and said drive sleeve in driving relation, and frictionally controlled 20 planetary driving connections between said drive sleeve and each of said drums and also arranged within said housing, each driving connection including a gear fixed to said drive sleeve and a planet gear carried by said 25 drum and meshing with said gear.
7. In a hoisting mechanism, a base, a cylindrical housing carried by said base, end closure members for said housing, a drive sleeve journaled within said end closure 30 members, relatively rotatable hoisting drums arranged within said housing and rotatably mounted on said drive sleeve, a motor carried by one end closure member, driving connections between 35 said motor and said drive sleeve including a transmission shaft arranged centrally within said drive sleeve, gearing connecting said shaft and said drive sleeve in driving relation, and frictionally controlled 40 planetary driving connections between said drive sleeve and each of said drums and also arranged within said housing, each driving connection including a gear fixed to said drive sleeve and a planet gear carried by said 45 drum and meshing with said gear and a frictionally controlled reaction gear with which said planet gear meshes.
8. In a hoisting mechanism, a base, a cylindrical housing carried by said base, end closure members for said housing, a shaft journaled within said end closure members, relatively rotatable hoisting drums arranged within said housing and rotatably mounted on said shaft, motor operated driving means for said shaft, and frictionally controlled 50 planetary driving connections between said shaft and each of said drums and also arranged within said housing.
9. In a hoisting mechanism, a base, a cylindrical housing carried by said base, end closure 55 members for said housing, a shaft journaled within said end closure members, relatively rotatably hoisting drums arranged within said housing and rotatably mounted on said shaft, motor operated driving means for said shaft, and frictionally controlled 60 planetary driving connections between said shaft and each of said drums and also arranged within said housing.
10. In a hoisting mechanism, a base, a cylindrical housing carried by said base, end closure members for said housing, a shaft journaled within said end closure members, relatively rotatable hoisting drums arranged within said housing and rotatably mounted on said shaft, motor operated driving means for said shaft, and frictionally controlled 65 planetary driving connections between said shaft and each of said drums and also arranged within said housing, each driving connection including a gear fixed to said shaft, a planet gear carried by each of said drums and meshing with said gear.
11. In a hoisting mechanism, a base, a cylindrical housing carried by said base, end closure members for said housing, a hollow shaft journaled within said end closure members, relatively rotatable hoisting drums arranged within said housing and rotatably mounted on said shaft, a motor supported by one end closure member, driving connections between 70 said motor and said shaft including a transmission shaft arranged centrally within said shaft, driving connections between said shafts, and driving connections between 75 said hollow shaft and each of said drums and also arranged within said housing, each driving connection including a gear fixed to said hollow shaft, a planet gear carried by the drum with which said gear meshes, and a frictionally controlled internal gear with 80 which said planet gear meshes.
12. In a hoisting mechanism, a support, a drive sleeve journaled within said support, relatively rotatable coaxially arranged hoisting drums rotatably mounted in substantially 85 end abutting relation on said sleeve, motor operated driving means for said drive sleeve including a transmission shaft arranged centrally within and rotatable relative to said drive sleeve and gearing connecting said transmission shaft and said drive sleeve, and a planetary slip control connection between 90 said drive sleeve and each of said drums, said planetary connections being arranged at 95 the remote ends of said drums.
13. In a hoisting mechanism, a support having upstanding end frames, a drive sleeve journaled within said end frames, relatively rotatable hoisting drums rotatably mounted on said drive sleeve, a motor attached to one end frame, driving connections between said motor and said drive sleeve including a transmission shaft arranged centrally within and rotatable relative to said drive sleeve and reduction 100 gearing between said transmission 105

- shaft and said drive sleeve and arranged within said other end frame, and a planetary slip control driving connection between said drive sleeve and each of said drums.
- 5 14. In a hoisting mechanism, a support, a drive sleeve journaled within said support, relatively rotatable coaxially arranged hoisting drums rotatably mounted on said drive sleeve and arranged in substantially end abutting relation thereon, motor operated driving means for said drive sleeve including a transmission shaft arranged centrally within and rotatable relative to said drive sleeve and reduction gearing connecting said transmission shaft and said drive sleeve, and a frictionally controlled driving connection between said drive sleeve and each of said drums, said driving connections being arranged at the remote ends of said drums.
- 10 15. In a hoisting mechanism, a support having upstanding end frames, a drive sleeve journaled within said end frames, relatively rotatable coaxially arranged hoisting drums arranged in substantially end abutting relation between said end frames and rotatably mounted on said drive sleeve, a motor secured to one end frame, driving connections between said motor and said drive sleeve including a transmission shaft arranged centrally within
- 15 and rotatable relative to said drive sleeve and reduction gearing arranged within said other end frame for connecting said transmission shaft and said drive sleeve and a frictionally controlled driving connection between said drive sleeve and each of said drums, said last mentioned connections being arranged at the remote ends of said drums.
- 20 In testimony whereof I affix my signature.
CHARLES F. OSGOOD.
